FIG. 5

UNITED STATES PATENT OFFICE.

EVERETT E. KENT, OF NEWTON, MASSACHUSETTS.

SAFETY DEVICE FOR TURNSTILES.

1,093,935.

Specification of Letters Patent. Patented Apr. 21, 1914.

Application filed June 4, 1913. Serial No. 771,585.

To all whom it may concern:

Be it known that I, EVERETT E. KENT, a citizen of the United States, residing at Newton, in the county of Middlesex and State of Massachusetts, have invented new and useful Improvements in Safety Devices for Turnstiles, of which the following is a specification.

This invention relates to safety devices for turnstiles.

At unattended exits from parks, places of amusement and other places to which an admission fee is charged, it is customary to provide turnstiles equipped with a ratchet and pawl to prevent people from passing in, but allowing them to pass freely out of the park. Where people use the same turnstile in rapid succession there is always danger that a person passing into it may be struck in the side or stomach by one of its arms, or may be caught or crushed between an arm and the adjacent stationary wall, because the arms have been set spinning by the person next previously passing through. Another danger is caused by the arms swinging backward a little, after passing their proper position to be at rest. These dangers are known to regular users, and are a constant cause of dread to the more timid or feeble, and especially to women. Notwithstanding the care usually exercised painful accidents occasionally happen; and companies that provide such turnstiles for their patrons receive demands for payment of considerable sums annually as damages. Even though no accident occurs the extreme care which users must exercise at crowded periods, and the incidental delay to all while each is waiting for opportunity to pass through safely, causes annoyance to users, restricts the capacity of the exit, and renders such turnstiles especially unfit where there is any danger of a crowd of people either escaping from a fire or for any other reason desiring to pass in haste. So far as I am aware no turnstile has been hitherto invented which will accomplish the main purpose of such turnstiles without the dangers mentioned.

Elimination of such dangers is one of the purposes of the present invention.

It is also an object of the invention to increase the "output" of such turnstiles.

It is a further object to control the operation of the turnstile automatically so that, no matter how ignorant, reckless or even vicious a preceding user may be, it is safe for the next person to enter the turnstile the instant the first has passed; and it is also the object to provide the other advantages which characterize the construction hereinafter described.

As such apparatus is used by all sorts of people, including strangers who may not have learned how to operate the device, it is necessary to the best form of the invention that the device should be operable by all comers, without previous instruction; and the invention provides a structure to accomplish this also.

In the accompanying drawings, which illustrate one embodiment of the invention: Figure 1 is a plan; Fig. 2 is an elevation of a fragment at the base, in section on the line 2-2 of Fig. 1; Fig. 3 is an elevation showing parts at the base and in the adjacent passage, in section on the line 3-3 of Fig. 1; Fig. 4 a plan of parts, in section on the line 4-4 of Fig. 3, on a larger scale; and Fig. 5 is a perspective illustrating a modification.

In Fig. 1 of the drawings a turnstile is represented, in which four arms 10 are surrounded by walls that are impassable except at the entrance 11 and the exit 12. As the features that constitute the invention may be applied to turnstiles of many types, the details which pertain strictly to the turnstile, and its mounting, need not be shown or described. The wall at the right is marked 13, that at the left 14 and there are stationary bars at 15 which prevent any person from entering at the regular exit 12 and reaching the regular entrance 11 by passing around the back of the turnstile. In the embodiment of the invention here represented the action of the turnstile is controlled by a ratchet 16 of peculiar shape, seen best in Figs. 1 and 4, and a pawl 17 pivoted on a rigid axis at 18. The ratchet is rigid on the central stock 9 of the turnstile. The teeth of the ratchet comprise

different surfaces marked respectively *a*, *b* and *c*. A single succession of these three makes a complete quarter of a circle, and corresponds to the distance which the apparatus turns in passing from one position where it is locked, at rest, and ready for a person to enter safely, as illustrated in Fig. 1, to the next position where it is again at rest, and ready for a person to enter safely. 5 which Fig. 1 serves also to illustrate, although in that position the individual arms would have been turned each through a quarter of a complete revolution. The surface *a* is terminated by an abutment *a'* at 10 one end and an abutment *a''* at the other end, the abutment *a'* being higher than the other but each being too high to pass the pawl 17 when the latter is in the position illustrated in Fig. 4. Rotation of the turnstile is therefore impossible in either direction. Under this condition of things the arms 10 occupy the positions A, B, C, D, except for whatever short distance the short surface *a* allows them to swing, this being 15 a little wider than the pawl to make sure of catching. The pawl 17 is maintained normally in this locking engagement with the ratchet wheel 16 by a spring 19, but may be retracted by swinging about its axis 18, 20 when the tail of the pawl is pressed to the left in Fig. 4 by a lug 20. When thus retracted far enough to clear the elevation of abutment *a''*, the ratchet wheel, and the turnstile, can rotate in the direction of the 25 arrow, the end of the pawl sliding along on the surface *b* and then on the surface *c* until it reaches the next depression *a* and is stopped from further movement by the abutment *a''* at the farther end thereof. 30 35 40 45 50 55 60 away from where it was stopped by the last previous abutment *a''*. The surfaces *b* and *c* each extend gradually outward. They are separated by an abutment *c'* approximately midway between the two locked positions of the turnstile just described, which constitutes a step down from *b* to *c*, adapted to engage the pawl to prevent the ratchet from being turned backward. An operating lever 21 having a limited possibility of movement is provided for moving the lug 20. In the embodiment of the invention here illustrated this lever is rigid on an axle or fulcrum rod 22 on which the lug 20 is also rigid, and is set in the floor of the passage which persons traverse while using the turnstile and is normally held upward by spring 26. To limit its depression an abutment 23 is so arranged that the movement of lug 20, when lever 21 is depressed to its utmost, corresponds to a swinging of the pawl 17 outward just enough to clear any of the abutments *a''* but not enough to clear either abutment *a'* or abutment *c'*, both of which terminate at greater radial distances from the center of

the ratchet wheel 16 than does the abutment *a''*. The lever 21 therefore may unlock the turnstile so that it can be rotated in the direction of the arrow, but not so that it can be rotated in the contrary direction. It will be seen that the lever 21 is in effect 65 a compressible section of the floor of the passage through which persons go in using the turnstile. It is a further feature of the invention that this compressible section is constructed far enough within that part of the 70 passage covered by the travel of the turnstile, so that no person standing naturally outside that area at the entrance 11 can be effectively standing upon it and preferably so that no person who is barely within that 75 area can be effectively upon it. It ends far enough from the exit 12 so that a person passing out or about to pass out there will have passed off of it; and it is located with respect to the turnstile arm position B so 80 that any person about to press on that arm to operate the turnstile will necessarily be standing on it and holding the lever 21 depressed until he has progressed far enough, and has rotated the turnstile far enough, 85 for the pawl 17 to have cleared the abutment *a''* and passed upon the surface *b*.

When arranged as illustrated, the arm 10 which is seen in position B, barring the passage in Fig. 1, will have traveled about 45° 90 to position B', about at the upper end of the wall 13, when the abutment *c'* passes the pawl and thus prevents regression of the turnstile from this position. When the arm has gone nearly 90° to position C, the 95 pawl engages beyond the next abutment *a'* and again prevents regression of the turnstile arms. Although the pawl 17 is capable of passing over the extreme height of these abutments *a'* and *c'*, the spring 19 yielding 100 when it does so, nevertheless the lever 21 cannot swing far enough to make the pawl clear these abutments but only far enough for it to clear the abutment *a''*. Consequently, the 105 apparatus cannot be manipulated by the 110 public so as to unlock it in such manner as to permit the turnstile to turn in the direction opposite to that of the arrow. It will be understood that the pawl itself may be 115 covered with a shield (not illustrated) or may be otherwise so arranged as to be inaccessible to the public to prevent anyone from getting at it directly with a stick or the like, in order to push it further against the spring 120 than it can be pushed by the lever 21.

Within the limits of location explained above, considerable variation in position of lever 21 may be practised, the position which is at present believed to be best being illustrated in the drawing. With the lever in 125 this position a person passes off of it while still within the confined area of turnstile and while the danger of hurting himself con-

strains him ordinarily to be managing the apparatus with care. If such a user give a push to the turnstile when departing, the pawl will be in position to stop it with the arms at positions A, B, C, D and the apparatus ready for the next person to enter.

The abutment a'' eliminates the danger of the arm illustrated at position D swinging past the position A and striking a person in the side while he, or she, is entering at 11, and the abutment a' eliminates the danger of the arm which has just arrived at position B swinging backward and thus hitting a person in front. The entrance is open so that the next person can enter as soon as the arm illustrated at A has reached A'. Any person who desires may wait until the positions A, B, have been reached; when the turnstile will be absolutely at rest; but if one does enter ahead of that, *i. e.*, while the arms are moving from the positions D', A', to A and B, that can be done with safety. If he enters immediately after the position A' is past, he will have reached the lever 21 and will have depressed it by the time that the next arm reaches the position A where ordinarily it should come to rest. The arm is therefore free to turn by that position, but it does no harm because the user is already so far advanced as to be safe. What more often happens is that a person attempting to enter thus does so somewhat slowly, not following closely the arm in front of him. Such a person is in danger, in turnstiles as hitherto built, of being struck by the next arm swinging past position A. But if he has been a little slow, and is still in the danger zone, he has not reached the lever 21, and therefore the pawl 17 will automatically check the arm at position A, whence it will be released an instant later when the person reaches the lever 21. The turnstile area may thus be said roughly to be divided into a vestibule 11', the turnstile being automatically locked when the user is there, (*i. e.*, by his absence from the lever space), and a lever space, the turnstile being automatically free to turn forward when the user is there; and the former being in a place where it is dangerous for the turnstile to swing freely, and the latter where it is desired that it swing freely.

In order to keep the apparatus permanently in good condition and unaffected by accumulation of dirt, a flexible apron 24 made of leather, linoleum or other suitable material is illustrated for excluding dirt. A space 25 is provided under the lever 21, in which a considerable amount of dirt may collect without interfering with the depression of the lever 21.

Fig. 5 illustrates another embodiment of the invention, in which the lever 21' is hinged at 22' to a plank 22" bolted on the

floor in the passageway through the turnstile, and a lug 20' fast on the lever 21' engages the tail of a pawl 17' that is adapted to engage the ratchet wheel 16 under the position A instead of under position B. A threshold strip 24' may be used as in the other case. This construction is somewhat simpler, can always be easily cleaned by swinging the lever 21' far upward on its hinge, and involves no excavation of the floor, but can be put in place anywhere by merely bolting down the plank 22". The spring 26' is attached to the under side of the lever 21'.

Many variations may be made from the structure hereinbefore described without departing from the scope of the invention as defined in the appended claims, the object of which is to cover in the patent whatever features of novelty exist in the invention disclosed. In particular, however, it may be noted that the lever is not necessarily located in position to be operated by the feet of the user; and that a different type or arrangement of pawl and ratchet, or of locking mechanism, may be used.

I claim as my invention:

1. A safety device for a turnstile comprising the combination, with the turnstile, of ratchet and pawl mechanism having tooth-abutments for preventing rotation in forward direction; higher abutments, facing oppositely, for preventing rotation in backward direction; and means positioned to be actuated by a person passing through to release the lower abutments without releasing the higher.

2. A safety device for a turnstile comprising the combination, with the turnstile, of ratchet and pawl mechanism having teeth facing in two directions and adapted to prevent rotation of the turnstile in either direction beyond points predetermined thereby; and means, engaged automatically by a person passing through, to release the teeth opposing his passage, leaving the others locked.

3. A safety device for a turnstile comprising the combination, with the turnstile, of means automatically stopping rotation of the turnstile in either direction at positions predetermined as being safe; and releasing means for rotation in one direction positioned in the path of and adapted to be actuated by a person entering the turnstile.

4. A safety device for a turnstile comprising the combination, with the turnstile, of means automatically preventing rotation of the turnstile arms across the turnstile entrance; and releasing means actuated automatically by a person passing through the turnstile and restricted by location so as to be actuated by such person only when he has passed the entrance.

5. A safety device for a turnstile comprising the combination, with the turnstile, of means automatically preventing rotation of the turnstile arms beyond predetermined positions; releasing means adapted to be actuated by contact of a person passing through, the passage through the turnstile being divided into predetermined areas of safety, and of danger, and said releasing means be-

ing arranged for operative contact of the person therewith only in the predetermined safe area.

Signed by me at Boston, Mass., this 28th day of May, 1913.

EVERETT E. KENT.
